UNITED STATES PATENT OFFICE.

JOHN E. COURTRIGHT, OF MONTGOMERY COUNTY, KANSAS.

COMBINED WEED-CUTTER, CULTIVATOR, AND PULVERIZER.

No. 800,206.

Specification of Letters Patent.

Patented Sept. 26, 1905.

Application filed March 31, 1903. Serial No. 150,418.

To all whom it may concern:

Be it known that I, JOHN E. COURTRIGHT, of Montgomery county, State of Kansas, have invented a new and Improved Combined Weed-Cutter, Cultivator, and Pulverizer, of which the following is a specification.

My invention relates to cultivators, and particularly to that class adapted to the cultivation of listed corn.

10 The object of my invention is to provide a new and improved cultivator for cutting the weeds on the sides of the furrow and for destroying the weeds and pulverizing the soil on the ridges and hilling the corn with any desired amount of clean soil; to provide a machine which can be easily guided in the furrow and which has rotary disks and cutting-blades capable of efficient adjustment in the various positions desired—that is, the disks 15 and cutting-blades may be adjusted to any required angle, also to any required depth, regardless of the position of the runners—and also means whereby each set of disks may be adjusted laterally and independently of the 20 other set.

My invention consists in various constructions and combinations of the same, as will be hereinafter described, and pointed out in the claims.

30 Reference will be made to the accompanying drawings, which form a part of this specification, and in which similar characters of reference indicate the corresponding parts of the different figures.

35 Figure 1 is a top plan view of the cultivator. Fig. 2 is a median longitudinal vertical section of the same, showing one-half of the sled, with the arrangement of disks, levers, cutting-blades, &c., with a part of the sled cut away 40 to show the connecting-rods *u* and *v*. Fig. 3 is a detail view of the casting or leg by means of which the end of the disk-carrying shaft or rod nearest or toward the sled-runners is held in proper position with reference to the adjustable pipe to which the upper part of the casting is attached. Fig. 4 is a detail view showing the bearings, boxings, and means of attaching the outside end of the disk-carrying shaft or rod to the adjustable pipe which 45 slides upon a rock shaft or rod held firm to the cross arch-bars of the cultivator-frame. Fig. 5 is a view of the mechanism for raising or lowering the disks, showing the arrangement of the lever by means of which the rock shaft or rod, upon which the adjustable pipes slide, is raised or lowered, thereby raising or 50

lowering the disks and also the sliding bearings upon the cross arch-bars, by means of which the rock shaft or rod upon which the adjustable pipes slide is held firmly to the 60 cross arch-bars of the cultivator-frame. Fig. 6 is a median vertical sectional view of the bearings and boxings at the outside end of the disk-carrying shaft, taken on a line parallel to the sled-runners.

65 The letters *A A* indicate the light metal framework of the sled-runners, consisting of upper frame-bars as well as lower runners. The runners are firmly held by the cross arch-bars *B B'* and the arch *e*. The runners are to 70 be from eight to fourteen inches apart, as may be desired, in order to straddle the row of corn growing in the furrow or trench in which listed corn is planted. The arch *e* and the cross arch-bars *B B'* are to be high enough to 75 pass over young corn without injury thereto. At the top the cross arch-bars are curved backward in an arc with a radius equal to the length of the rod *u* in order that the upper part 80 of the rock-shaft *M* may be guided between these arcs by means of guide-lugs *5 5*, which extend outward at the upper bend in the rock-shaft *M*, and thereby hold the disks firmly in position at all times when the disks are raised or lowered.

85 The cross arch-bars *B B'* are attached to both the upper frame-bars and the runners *A A* by means of bolts, as shown in Fig. 2. The guiding-feet *f f* are attached to the arch *e* and to the frame of the runners *A*. The 90 lower ends of the guiding-feet are turned or bent backward in line with the runners, which runners are bent upward in front and follow a short space behind these feet. In the space between the runners and the feet are the cutting-blades *E E*. These blades are adjustably attached to the bars *m* by means of bolts and the slots *n*. Said bar *m* is also adjustable by means of holes or apertures in said bar at the 95 points where the bar is attached to the frame *A* and to the guiding-foot *f* in order that the depth of the blade *E* may be changed with reference to the runners. Said bar is further adjustable by means of holes or apertures in the guiding-foot *f* and holes or apertures in 100 the upper part of said bar, whereby the slant of the cutting-blades may be changed so as to shave the sides of the furrow.

105 The rock shaft or rod *M*, which passes between the cross arch-bars *B B'* in the sliding bearings *s s*, is bent upward just inside of the cross arch-bars *B B'*, forming an arch which

works inside of the cross arch-bars B B' upon guide-lugs 55, as shown in Fig. 5. These lugs extend outward at the upper bend in the rock shaft or rod M between the cross arch-bars 5 B B', and thus the backward curve in the cross arch-bars B B' rocks the rock shaft or rod M in such a way as always to keep the sets of disks at the same distance from the bars j j, to which they are firmly held by the 10 rods u u when the disks are raised or lowered by means of the lever D raising or lowering the rock shaft or rod M.

Standards P P are attached at their lower 15 ends to both the upper and lower frame-bars of the runners A and A and then extending upward they are bent backward in their upper part and attached to the arch cross-bar B.

q is a rock-shaft journaled in bearings Z Z 20 on the standards P P. One end of this shaft has an angular rearwardly-extending arm q' outside of the bearing, which is slotted at its rear end at D'. Secured to the shaft q, outside of the other bearing Z, is a lever D, which 25 has a pawl r, adapted to engage the segment R, secured to the standard P. The lever D has a rearwardly-extending arm parallel to the arm q' of the shaft q and also slotted at its rear end. The slots of D and q' engage 30 the lugs projecting from the outside of the vertically-sliding bearings s s, and by means of the rock-shaft, lever, and rack the bearings can be adjusted vertically.

The pipe K is slipped over the end of the 35 rock shaft or rod M and secured preferably by means of the set-screws 77 in such a manner as to be adjustable upon the rock shaft or rod M. The ends of the rock shaft or rod M may be made either round or square, as may 40 be desired. The leg W is rigidly secured to the end of the pipe K which is nearest or toward the runners by means of the U-shaped bolts 88. The lower end of the leg W is forked, having in the forks slots i i running 45 transversely, so as to allow the bearings around the shaft p, and thereby the inner end of the shaft p, to be drawn forward and let back. The outward end of the pipe K is bent downward at right angles, as at K'. To the lower 50 end are attached castings X X' by means of the bolts 69. Within said castings X X' are other castings Y Y', which inclose the boxings of the disk-carrying shaft p. Said castings Y Y' are secured to each other by means 55 of small bolts, as shown in Fig. 4. One of these castings Y' fits into a groove in the casting X. Said groove runs transversely and allows casting Y' room to slide horizontally. The other of these castings Y fits into a groove 60 in casting X', which also runs transversely. This said casting Y is also pivotally attached within casting X' by means of the vertical bolt 10, which passes through these castings at the place where casting Y fits into the groove 65 in casting X' and so adjusted as to allow cast-

ing Y to swing freely horizontally upon said pivot in casting X'.

The bars j j are attached by any suitable means to the upper and forward portion of the frame of each of the runners, respectively. Then extending outward and back they are bent in such a manner as to pass through plate 2 and extend horizontally at right angles to the sled-runners. The bars a a are attached toward the rear onto the upper portion of the frame-bars of each of the runners and then extend outward and forward in such a manner as to pass directly beneath plate 2 at the bends in the bars j j and furnish a base for the attachment of plate 2, which has a segment-rack 80 upon it, and pivotally attached to said plate 2 is the lever 1. Said lever 1 has pivotally attached to it the draw-rod v. Said draw-rod v is attached at its rear end by any suitable means to the bearings on the disk-carrying 85 shaft, thereby making it possible to adjust the disks to any angle desired by throwing the lever 1 forward and backward. The rod u is pivotally attached at its forward end to the bar j by means of the casting k², which is made 90 adjustable upon said bar j by means of a set-screw. Said rod u is also pivotally attached at its rear end to the U-shaped head of the bolt 6.

The bars j j are braced by the rods H H extending from the bars j j to the lugs 3 3 on the outward ends of the bars a a, being secured thereto by means of nuts.

As the sled is drawn forward by means of the draw-rods g the knives E E cut the weeds 100 along the sides of the furrow. The depth to which it is desirable to cut the soil upon the ridges is regulated by forcing the disk gangs into or out of the ground by means of the lever D, and by this means the disk gangs can 105 also be regulated to the depth of the furrow in which the corn is listed. The thoroughness with which the soil is to be turned is regulated by the levers 1 1 being drawn forward or let back and thereby giving the disk gangs more 110 or less slant. The distance of the disk gangs from the corn, and thereby the amount of soil thrown around the corn, is regulated by adjusting the disk gangs in toward or outward 115 from the sled upon the rock-shaft M.

Having thus described my invention, what I claim as new, and wish to secure by Letters Patent, is—

1. In a combined weed-cutter, cultivator and pulverizer the combination of parallel runners with sufficient space for the plants to pass between them when the sled is drawn forward; two parallel cross arch-bars, said cross arch-bars being curved backward in an arc in their upper portion; a rock shaft, or rod, which 120 works upon sliding bearings between these cross arch-bars, said rock-shaft being bent upward just inside of these cross arch-bars in the form of an arch with guide-lugs extending outward at the upper bends in said arch 125 130

between the curved portion of said cross arch-bars; and the said guide-lugs, all substantially as shown and described.

2. In a combined weed-cutter, cultivator and pulverizer the combination of parallel runners suitably connected; the cross arch-bars a rock-shaft working in sliding bearings upon said cross arch-bars; two gangs of perpendicularly and angularly adjustable disks; the laterally-adjustable pipe upon said rock-shaft; the means of attaching said disks to said adjustable pipe upon said rock-shaft; the means of securing said pipe in adjusted position upon said rock-shaft; the means for raising or lowering said rock-shaft upon the cross arch-bars; and also the means for keeping the sets of disks always at the same distance from the point from which they are drawn, comprising draw-rods pivotally connected with the bearings at the outer ends of the disk-gangs and extending forward and pivotally connected with the cultivator-frame; and draw-rods pivotally connected with and extending forward from the bearings at the inner ends of the disk gangs and pivotally con-

nected with levers upon the cultivator-frame, all substantially as shown and described.

3. In a combined weed-cutter, cultivator and pulverizer the combination of two parallel runners suitably connected; two sets of laterally, perpendicularly and angularly adjustable rotating disks; the bars extending horizontally outward from said runners on each side of the sled, one of said bars extending outward and forward and the other outward and backward; the means of attaching the sets of disks to said bars; also means whereby the angular position of the disks may be controlled; and the cutting-blades, and the means of adjusting said blades to the depth and slant required all substantially as shown and described.

In testimony whereof I have signed my name to this specification in the presence of two subscribing witnesses.

JOHN E. COURTRIGHT.
